CLAIM

The ornamental design for a merchandise display, as shown and described.

DESCRIPTION

FIG. 1 is a perspective view of a merchandise display showing our new design, the broken line showing of a second display being for illustrative purposes only; FIG. 2 is an enlarged perspective view of a display unit for the merchandise display;

FIG. 3 is a side view of the display unit of FIG. 2; FIG. 4 is a front view of the display unit of FIG. 2;

FIG. 5 is a top view of the display unit of FIG. 2; FIG. 6 is a bottom view of the display unit of FIG. 2;

FIG. 7 is a back view of the display unit of FIG. 2; FIG. 8 is an enlarged, fragmentary view of the tiered shelves for the display unit of FIG. 2;

FIG. 9 is an enlarged fragmentary view of the slat wall bracket for the display unit of FIG. 2; and,

FIG. 10 is an enlarged, fragmentary view of the display shelf for the display unit of FIG. 2.
